UNITED STATES PATENT OFFICE.

WILLIAM J. TYNON, OF DUNKIRK, NEW YORK.

LUBRICATOR.

SPECIFICATION forming part of Letters Patent No. 439,795, dated November 4, 1890.

Application filed July 24, 1890. Serial No. 359,785. (No model.)

To all whom it may concern:

Be it known that I, WILLIAM J. TYNON, of Dunkirk, in the county of Chautauqua and State of New York, have invented certain new and useful Improvements on a Lubricator; and I do hereby declare that the following description of my said invention, taken in connection with the accompanying sheet of drawings, forms a full, clear, and exact specification, which will enable others skilled in the art to which it appertains to make and use the same.

This invention has general reference to improvements in lubricators; and it consists, essentially, in the novel and peculiar combination of parts and details of construction, as hereinafter first fully set forth and described, and then pointed out in the claims.

In the drawings hereinbefore referred to, Figure 1 is an elevation of my improved lubricator. Fig. 2 is a longitudinal sectional elevation. Fig. 3 is a plan of the same.

Like parts are designated by corresponding letters of reference in all the figures.

The object of this invention is the production of a simple lubricating oil-cup for shaft-bearings and the like, which can be regulated to feed a certain quantity of lubricant in a predetermined space of time, and which can be entirely stopped by simply turning a lever. To attain this result, I construct my lubricator substantially as shown in the drawings, and in which—

A designates the bottom piece of my lubricator, it being provided centrally with an upwardly-projecting tube F, the upper end of which passes through an aperture in the top piece B, as shown in Fig. 2. Between these top and bottom pieces is interposed a glass cylinder C, thereby producing a tight chamber D for the reception of the lubricant, washers d d' being placed between the edges of the cylinder and the top and bottom pieces to make a tight joint.

The tube F, before mentioned, is provided with a passage o, leading into its interior from the chamber D, for the escape of the lubricant, and it has at its upper end an external screw-thread, over which fits a cap H.

The top piece B has in its upper surface and surrounding the tube F an annular boss P, over which fits a plate G, as clearly shown

in Fig. 2. The lower surface of this cap H bears against the boss p, whereby by screwing it over the end of the tube F the pieces 55 A, B, and C are brought into close contact. This cap H has in its upper end V-shaped notches h' on diametrically-opposite sides, thereby forming a double cam, which is engaged by downwardly-pointing similar projections i on a lever I, there being provided notches h'' in the crowns of the cams h' for the reception of the points i of the lever I, as clearly illustrated in Fig. 1.

Within the bore of the lever I, as well as 65 the cap H and the projection h, there is located a tubular sleeve K, fitting therein with a sliding fit, and which is provided at its lower extremity with a flange k, said sleeve being soldered or otherwise secured to the 70 lever I at its upper end. The inner bore of the sleeve K is internally screw-threaded for the reception of the externally-screw-threaded portion n of a spindle N.

In the interior of the tube F, between the 75 flange k and the cap H, there is located a spiral spring R to force the said sleeve downward.

The bottom piece A is provided centrally with a downwardly-pointing boss c, having a 80 nozzle P. In the interior of this boss and nozzle there is a passage o', communicating with the interior of the tube F, a valve-seat a being located in said passage, so that it may be closed by a needle-point a' on the lower 85 end of the spindle N, as shown in Fig. 2.

Over the screw-threaded boss c on the bottom piece A fits a cup-shaped body E, provided with openings e'', which are preferably fitted with glass disks, through which the passage of the lubricant from the nozzle P may be seen. This cup has at its lower end the usual shank e, provided with a wrench-section e' for screwing the lubricator into position.

The lever I is provided with a handle I', wherewith it may be revolved, and the spindle N has at its upper extremity a button N' (having a pointer M, as hereinafter described) for regulating the feed of the lubricant. 100 Upon the screw-threaded portion n of the spindle N is located a disk J of proportionately large diameter, and having upon its upper face a series of radial divisions J', rep-

resenting predetermined amounts of lubricant that will escape from the lubricator in a fixed space of time, so that the operator may regulate the amount of the outflowing liquid in a manner hereinafter to be referred to.

To fill the chamber D, there is an aperture b in the top piece B, and which is closed by the plate G, before mentioned.

In the present instance the divisions on the face of the disk represent drops of liquid discharged per minute, although other suitable graduation may be used, and the pointer M is so arranged on the spindle N with respect to the dial that when the said spindle is upon the valve-seat a and the cam I seated, or in the position shown in Fig. 2, the said pointer M will indicate the largest quantity of lubricant that can pass out of the chamber D within said time, when the lever I is partly revolved and seated in the notches in the crowns of the projections h, as shown in Fig. 1. Should it be desired to lessen the quantity of lubricant passing from the lubricator, the lever is again seated in the bottom of the notches, and then the valve-spindle turned by the button until the desired quantity is indicated by the pointer, when the lever I is again raised and the lubricator resumes its function. It is evident that when the lever is completely depressed and the spindle revolved the sleeve K will rise and with it the lever I, thereby giving the lever I less lift when afterward revolved, for obvious reasons. It is also evident that the disk J serves the double purpose of an indicator-dial and a lock-nut to prevent the spindle N from being freely revolved, it being borne in mind that the disk J when turned in the proper direction binds the spindle N to the tube in the manner of a lock-nut, while slightly loosening it enables the spindle to be revolved by the button N'. This disk, however, when screwed down upon the tube will always return to the same spot relative to the tube, and will therefore not affect the proper indications of the pointer M.

One of the advantages of my device over others is that I can easily grind the valve stem and seat to a tight fit in case of leakage by simply revolving the spindle until the

sleeve and lever have been screwed up high enough to clear the projections h, when by turning the handle I' the spindle may be revolved to grind or wear the spindle to the seat, the spiral spring R in this case assisting in pushing the valve to its seat.

This device can be produced at a very low cost, it being composed of comparatively few parts, requiring but little time and labor to manufacture. It is preferably produced in brass, so that it may be readily polished and plated, and when so finished will present a very neat and attractive appearance.

Having thus fully described my invention, I claim as new and desire to secure to me by Letters Patent of the United States—

1. The improved lubricator hereinbefore described, consisting, essentially, of the top and bottom pieces and the interposed glass cylinder, the tube centrally upon the bottom piece passing through the top piece and screw-threaded at its upper end and provided with an aperture and a valve-seat at the bottom of the tube, the cap screwed to the upper end of said tube and bearing against the top piece and provided with cam-shaped projections at its upper end, the cam-shaped lever engaging said cams, the internally-screw-threaded sleeve within said tube having the flange at its lower end, the spiral spring interposed between the flange and cap, and the screw-threaded valve-spindle having the button and lock-nut, as and for the purpose set forth.

2. In lubricators, the combination, with the oil-reservoir, of the cap H on the upper end thereof, the cam-shaped projections on the upper end of said cap, the cam-lever engaging the same, the interiorly-screw-threaded sleeve, the valve-spindle provided with the pointer on its upper end, and the combined lock-nut and disk having the graduations in its face, substantially as and for the object stated.

In testimony that I claim the foregoing as my invention I have hereto set my hand in the presence of two subscribing witnesses.

WILL. J. TYNON.
